UNITED STATES PATENT OFFICE.

CHARLES THEODORE HENNIG, OF BUFFALO, NEW YORK, ASSIGNOR TO
JAMES R. HATMAKER, OF NEW YORK, N. Y.

MEANS FOR UTILIZING FUEL.

SPECIFICATION forming part of Letters Patent No. 609,744, dated August 23, 1898.

Application filed December 2, 1897. Serial No. 660,557. (No model.)

To all whom it may concern:

Be it known that I, CHARLES THEODORE HENNIG, a citizen of the United States of America, residing in the city of Buffalo, in the county of Erie, State of New York, have invented a certain new and useful Improvement in Methods of and Means for Utilizing Fuel, of which the following is a specification.

My invention has reference to a method and means for supplying fuel to furnaces for all purposes, so as to obtain perfect combustion thereof, and also to a method and means for utilizing the high temperature of perfect and rapid combustion in boilers and furnaces without injury thereto, and, thirdly, in its more specific aspect my invention includes means for adapting the above to the purposes of railway-work.

My invention is exemplified in the accompanying drawings, wherein—

Figure 1 is a section of one form of tender for locomotives suitable to the application of my invention to railway-work. Fig. 2 is a section of a portion of the feed apparatus which may be used in tenders or elsewhere, showing a modification of the form shown in Fig. 1. Fig. 3 is a vertical section of a portion of one form of locomotive as fitted out with an example of constructions coming within my invention. Fig. 4 is a section of a portion of the fuel-feed apparatus, shown on a larger scale than in Fig. 3; and Fig. 5 is a view similar to Fig. 3, but showing a modification of my invention contemplating induction by the use of a stream of steam.

It is to be understood that although the accompanying drawings illustrate the application of my invention to boiler purposes the same is applicable to any furnace for any purpose and that I am not limited to the application of my invention to locomotive or other single specific purposes. The illustrations herewith given are rendered necessary for the exposition of the more specific features of my invention whereby it is adapted to locomotive-boilers; and the invention being thus exemplified in one form, illustrations of other applications thereof are rendered unnecessary, as they involve changes obvious to those skilled in the art.

My invention, taken from the point of view

of a novel method of feeding fuel for all purposes, involves the pulverizing of solid fuel and the forcing thereof into the furnace by submitting the same to the pressure of an elastic fluid, such as steam, gas, or air.

I have found that where solid fuel, such as soft coal, is pulverized to great fineness it may be forced out of a containing vessel through a comparatively small opening by the pressure of an elastic fluid behind it. Where the fuel-feed is periodically interrupted, I prefer to supplement the action of the pressure behind the fuel by a stream of air, steam, or gas, so directed as to coöperate by induction to drive the fuel through the delivery-pipe in the manner shown in the drawings. This feature will be understood to be applicable, of course, in those cases where the feed is not interrupted.

Whether fed in connection with the use of the induction-pipe or not, the fuel should be mingled with a proper proportion of air for complete combustion.

One means for carrying out my process in connection with locomotive-engines is shown in the drawings, wherein the magazine for storage of fuel in a pulverized state is shown in the usual tender at 1. The dotted line indicates the level of the fuel when at its highest.

The floor of this storage-magazine should be so shaped as to promote movement of the particles of fuel toward the opening 2. The curves indicated in the drawings at 3 will be found appropriate for this purpose. In the practice of my method of fuel-feed the pulverized fuel is driven out of the opening or pipe 2 by means of air-pressure within the space above the dotted line in Fig. 1. This pressure should be supplied from a proper air-storage tank, which I have shown at 4 under the tender, although it will be understood that the position of this tank is not essential to my invention. The main object of the tank 4 is to make provision for starting up a cold engine. Proper pressure should always be maintained in this tank when the engine is allowed to grow cold, as it is necessary to have such pressure for the purpose of fuel-feed. In the case of a locomotive the storage-tank can be supplied from the same system that supplies the air-brakes, as

through the pipe 5, (see Fig. 1,) and this arrangement is shown in the drawings by the connection of the pipe 5 with the air-pump 6 on the engine. (See Fig. 3.) Of course the 5 pump that supplies the fuel-feed pressure may be separate from the air-brake system altogether, if so desired.

In Fig. 5 I have shown a modification where-in the induction is produced by blowing live 10 steam directly from the boiler through a pipe, such as 6^a, into the fuel-supply pipe. This may in some cases be preferred to the use of the compressed air.

It will of course be understood that the 15 magazine for fuel-storage is tightly closed, the fuel being introduced, preferably, by chutes through the door or other opening 7. I prefer to make this door swing upon a hinge, as indicated by the dotted lines in the figure, 20 and to weight it so that it may act as a safety-valve in the case of accidental production of dangerous pressure within the fuel-magazine by any cause. Those parts of the tender not 25 occupied by the fuel or compressed air serve for storage of water, as in the present system. The valve 8 serves to confine the air within its tank when not in use.

I prefer to use, in connection with my fuel-magazine and elastic fluid under pressure, as 30 above described, a pipe for producing an induced current of air and fuel at the point of delivery from the magazine. This is particularly desirable where the magazine is stationary and where the supply is intermittent 35 in character.

One form of pipe for this purpose is shown in Fig. 1 at 9. This pipe opens at the top into the air-space above the fuel and is thus fed from the same mass of air as produces 40 the initial pushing power for the feed. The delivery end of this pipe is placed just at the outlet of the magazine, in such a position and so pointed that it will tend to find an outlet with the fuel. The rush of air or gas through 45 this pipe 9, acting by induction upon the surrounding fuel, will aid in the delivery of the fuel through the pipe 2. This description applies as well to the pipe 6^a. (Shown for carrying steam in Fig. 5.) Of course the 50 steam induction may be used with or without the pressure of air behind the mass of fuel.

In order to control the delivery of air through the pipe 9, the valve 10 is used, and by this control the volume of fuel delivered 55 is regulated without materially disturbing the proper proportion of fuel and air. A valve, such as a slide 11, may be used to entirely close the opening 2 when the supply is to be interrupted for any reason.

60 As shown in Fig. 2, the induction-pipe need not necessarily lead from the chamber above the fuel where the compressed air is used. For instance, the pipe 12 may be used under the magazine or tender, leading directly from 65 the storage-tank 4 or from any other desired portion of the compressed air or gas system.

As above stated, the current of fuel and

air driven from the opening 2 is preferably so treated after delivery as to bring into operation an added volume of air. This is done 70 in order that the driving or feed of the fuel may be accomplished with less compressed air than that necessary to accomplish perfect combustion. This step in the process of feeding the fuel is therefore best adapted to 75 that modification of my system wherein compressed air is the driving agent, although it is also more or less appropriate to other modifications. I prefer to carry out this step 80 in the feeding process by means of the apparatus shown on a large scale in Fig. 4. Here the delivery end of the pipe 2^a, through which the fuel is fed, projects into an entrance-flue 13, provided with perforations, as indicated at 14, through which the air moves, as shown 85 by the small arrows. Air is also sucked into this flue by the annular space between it and the pipe 2^a and becomes mixed with the air and fuel delivered. The wall of the furnace thus supplied is indicated at 15 in Fig. 4, and 90 I prefer to give the flue 13 a flaring shape within the furnace, as shown at 15.

I have thus far described my invention broadly in its application to any form of furnace for any purpose, and I have limited my 95 description to that aspect of my invention which has relation simply to the novel method or process for supplying fuel by pulverizing the same and driving it through the feedway by means of a mass of compressed elastic 100 fluid. Where perfect combustion of fuel is rapidly produced, however, as is the case with the apparatus used as above described, a very intense heat is generated, and the temperature is carried so high as to have a rapidly- 105 destructive effect upon all but the most refractory materials, and even when used for heating water a furnace fed as above described and in which complete combustion is carried on must be provided with proper 110 means for preventing the burning of the material of the boiler.

The construction which I have devised for the purpose of thus safely using fuel with all the economy incident to rapid and perfect 115 combustion is described hereinafter and is capable of use with any system wherein the fuel used is mixed with the necessary supporter of combustion and projected into the furnace to be burned as fast as fed. I may therefore 120 use oil or gas or any hydrocarbon vapor or liquid in connection with my improved form of furnace about to be described. It will be understood that the use of a driving fluid-pressure such as I have described above will 125 be unnecessary with liquid or gaseous fuels, although my invention is broad enough to cover such use when desired.

One form of safety-furnace for boilers is indicated in Fig. 3, which illustrates one well-known form of fire-box for locomotives, wherein the fire-space is surrounded by a water-jacket 17, communicating with the boiler. In 130 using my method of fuel-feed in connection

with a boiler I line the furnace with fire-brick, closing all entrances to the box save that at the flue 13.

The iron parts of the boiler are completely shielded from the flame, which is projected into a combustion-space 18, directly in front of the flue 13. This is the first of a series of flues and chambers built up of fire-brick on the principle of the regenerative furnace, wherein the products of combustion are forced through winding passages, somewhat as shown in Fig. 3. As these hot gases are thus led among the bricks they give up their heat to the latter, raising them to a high heat, and finally reach the beginning of the boiler-flues at such a temperature as is not injurious to the iron. They then pass through the flues in the ordinary way, it being understood, however, that the usual forced draft employed in locomotives will not be essential where my invention is employed.

The result of the use of the construction thus described is the production of a flame of extremely-high temperature and corresponding economy from a relatively small amount of fuel. This high temperature is confined to the center of the brick-flue system, in which is located the combustion-chamber. From this center of maximum temperature the heat is transmitted outwardly to the protected sides of the fire-box and reaches the iron of the boiler in the form of heat at a relatively low and quite harmless temperature. The fuel should be fed with a due regard to the average temperature of the fire-brick within the furnace, and when this temperature becomes too high, instead of opening doors over a fire, as is done in the present form of boiler fire-box, the engineer simply shuts off the fuel-supply and relies upon the heat already stored in the bricks to run the engine until it becomes necessary to again turn on the stream of fuel. The reignition of the fuel as it enters is accomplished by the heat of the fire-box itself.

In starting the fire it will be found best to raise the whole interior of the fire-box to a sufficiently high temperature to ignite the mingled coal and air when they are turned on, which may be accomplished in many ways known in the art, such as by burning various forms of fuel within the furnace.

It will be found best to leave a space beneath the entrance-point of the fuel, where my pulverized-coal system is used, for the reception of the small amount of ash which is liberated. This is shown at 20 in the drawings.

The pipe 2^a is a continuation of the pipe 2 in Fig. 1, as is shown by the coupling 21 in Figs. 1 and 3. This coupling is of course a detail incident to locomotive-work.

It is to be understood that the details of construction above described in connection with the fire-box are merely those which I prefer in the ordinary form of locomotive fire-

box as known at the present time, but that said construction is susceptible of many variations without departing from my invention. For instance, the furnace may be more or less lined with fire-brick or other protecting-sheath, depending upon its size and the proximity of the flame to the iron. Contact of the flame with the flues or other iron parts of the boiler is to be avoided, and it is the main object of this part of my invention to deflect said flame from following its natural course into the flues by centering it in a brickwork construction, from which its heat radiates.

Many details of my invention may be varied without departing from the spirit thereof, and I wish it understood that the actual forms and shapes shown and described hereinbefore are purely examples of those coming within the terms of my claims.

What I claim is—

1. As a means for delivering pulverized fuel for combustion, a storage-magazine having an outlet for the fuel, means for producing gaseous pressure on that side of the fuel away from said outlet, and a pipe leading through the body of said fuel, from the pressure-chamber to said outlet, substantially as described.

2. In a means for delivering pulverized fuel for combustion, a flaring flue in the furnace-wall, and a pipe for fuel delivery of smaller diameter than said flue, directed into the same.

3. In a means for delivering pulverized fuel for combustion, a flaring flue in the furnace-wall having perforations in that part which is outside the wall, and a pipe for fuel delivery of smaller diameter than said flue, entering said perforated portion of the flue.

4. A boiler, a fire-box therefor, and means for delivering pulverized fuel and air to said box, in combination with a lining of refractory material for said fire-box, and passages formed of refractory material and offering large radiating-surfaces to the burning fuel, within said box.

5. In a locomotive-tender, a substantially air-tight chamber for storing fuel, having a delivery-outlet, and a feed-door; a storage-tank for compressed air connected to the upper part of said fuel-chamber by a pipe; and an induction-pipe and connected source of gaseous pressure, said pipe leading to said outlet-opening.

6. As a means for fuel feed on railway-trains provided with an air-brake system, a substantially air-tight closed tender for fine fuel or its equivalent, a connection with the air-brake system leading to the top of said tender, an outlet for said fuel leading to the locomotive, an induction-pipe discharging at said outlet and means for supplying a fluid under pressure thereto.

CHARLES THEODORE HENNIG.
